PIN STEM CLUTCH

Carl H. Okerholm, Lakewood, and Attilio Pasquale, Providence, R. I., assignors, by mesne assignments, to American Metal Crafts Company, a corporation of Massachusetts

Application March 11, 1943, Serial No. 478,824

9 Claims. (Cl. 24—155)

This invention relates to a device for gripping a pin stem or shank which may extend through the clothing from some emblem or button which it is desired should be mounted on a garment.

Devices of this character usually have the actuation mechanism formed of screw machine parts with the body being formed of two sheet stock parts rolled together, leaving a hollow central portion which houses the operating mechanism. Brass is usually used for the formation of a device of this character, but due to the scarcity of copper and other metals, we desire to reduce to a large extent the metal heretofore used, and further we desire to provide a less expensive overall operation.

One of the objects of this invention is to provide a device for gripping a pin stem or the like in which the actuating mechanism will be formed of sheet stock press formed parts.

Another object of the invention is to provide an actuating mechanism which may be produced more quickly than heretofore.

Another object of the invention is to provide a construction which may be quickly and inexpensively assembled.

With these and other objects in view, the invention consists of certain novel features of construction, as will be more fully described and particularly pointed out in the appended claims.

In the accompanying drawing:

Fig. 1 is a central sectional view showing a pin or shank inserted in this device;

Fig. 2 is a sectional view at right angles to the showing of Fig. 1;

Fig. 3 is a sectional view on line 3—3 of Fig. 1;

Fig. 4 is a sectional view on line 4—4 of Fig. 1;

Fig. 5 is a perspective view of a portion of the cage for holding the rolls of the clutch;

Fig. 6 is an elevational view of the cage with a tubular part assembled therewith;

Fig. 7 is a sectional view of the cap handle for manipulating the clutch; and

Fig. 8 is a sectional view of the lower part of the body or housing.

In proceeding with this invention instead of using a screw machine product formed from solid stock bored out to shape the controller of the gripping elements, we have utilized roller type gripping elements and provided a sheet metal controller formed by blanking and bending by simple press operations and have utilized certain resiliency in the folding or bending of the controller to additionally function in the actuating mechanism. The controller serves to hold the gripping elements in proper position for recep-

tion of the pin stem or shank to be gripped by the clutch and also serves as a means for moving the gripping elements, or releasing means, for conveniently limiting the movement of the controller.

With reference to the drawing 10 designates generally the lower portion of the body member which consists of a disc 11 drawn or embossed to provide a cup 12 providing a generally rectangular recess 13 with tapered side walls 14 and a bottom wall 15 provided with an axial opening 16 for the reception of a pin stem or shank 17. A flange 18 extends upwardly from the disc 11 and is shouldered as at 19 for the reception of the upper or other portion 20 of the body. This upper portion 20 consists of a domed disc 21 having laterally extending edges 22 to rest upon the shoulders 19 and be held in this position by the rolling inwardly, as at 23, of the upper edge of the flange 18. This provides a hollow shell-like body for retaining the operating or actuating mechanism. The top 24 is raised from the portion 20 and is provided with a central opening 25 in axially aligned relation with the opening 16 in the bottom wall of the opposite body portion.

The gripping means comprise elements in the form of rolls 26, see Figs. 1 and 3, which are manipulated by a controller member designated 27 consisting of a sheet metal piece 28 folded into generally U-shape, as shown in Fig. 5, with leg portions 29 bent downwardly from the arched bridge 30 to extend toward each other and then outwardly as at 31 in an arc shape to receive the gripping element 26, the arc being of a diameter to revolvably support the gripping element. Each of these legs are centrally cut out as at 32 while the bridge 30 is cut out as at 33 to provide a central passage therethrough for the accommodation of the shank or pin stem. Arms 34 extend laterally from the bridge 30 to engage the top portion of the body to limit the axial movement of the controller member.

The opening 33 also serves to receive the tubular part 35 of the gripping means which has a flange 36 extending beneath the bridge 30 of the controller member. This tubular portion 35 extends outwardly from the body through the opening 25 and has a cap 36 secured thereto, serving as a handle. The cap is in two pieces there being a disk rolled inwardly over the flanged edge of the tube 37. This tube 37 has a press fit with the upper edge 38 of the tubular portion 35 which holds these parts assembled. Thus, a convenient handle is provided outwardly

of the body. A spring 39 surrounds the tubular part 35 engaging the raised portion 24 as an abutment and presses upon the portion 30 of the controller to move it axially toward the bottom wall 15 as shown in Fig. 1 so as to move the gripping element into the smaller and more confined part of the recess 13.

The gripping elements in moving into the more confined part of the recess will force the bent legs 29 inwardly toward each other and place these legs under an inherent tendency to expand or move away from each other so that when the handle 36 is engaged and the controller is moved axially away from the wall 15 these legs will tend to expand or move away from each other and will also move the gripping element 26 away from each other so as to release the pin stem or shank 17 which is positioned between them. The movement of the gripping means to released position is limited by the arms 34 engaging the arched wall 21 so that the controller or rolls can never move completely out of the recess.

When the shank 17 is inserted it will itself move the rolls to a position where they may freely rotate by forcing the controller and the gripping element inwardly or upwardly as shown in Fig. 1. The pin stem in entering may do so easily by the rolling of the gripping elements and when these are moved to a position so that they are free to turn they serve as an easy means for extracting the shank from position.

We claim.

1. A pin stem clutch comprising a body provided with a recess having tapered guiding surfaces and a bottom wall with an axial opening therethrough for the reception of a pin stem, axially movable gripping means having a portion located in said recess and comprising a pair of gripping elements engaging said tapered surfaces to be moved toward each other by the surfaces as they move toward said bottom wall, a controlling member formed of sheet material and folded into substantially inverted U-shape to have its leg portions disposed between said gripping elements on opposite sides of said axial opening with the end portion of each leg extending outwardly to engage and support one of said elements to diametrically locate said elements on opposite sides of the axis of said opening and for movement of said elements axially away from said bottom wall whereby said elements may move away from each other.

2. A pin stem clutch comprising a body provided with a recess having tapered guiding surfaces and a bottom wall with an axial opening therethrough for the reception of a pin stem, axially movable gripping means having a portion located in said recess and comprising a pair of gripping elements engaging said tapered surfaces to be moved toward each other by the surfaces as they move toward said bottom wall, a controlling member formed of sheet material and folded into substantially inverted U-shape to have its leg portions disposed between said gripping elements on opposite sides of said axial opening with the end portion of each leg extending outwardly to engage and support one of said elements to diametrically locate said elements on opposite sides of the axis of said opening and for movement of said elements axially away from said bottom wall whereby said elements may move away from each other and a spring engaging said member to move it toward said wall.

3. A pin stem clutch comprising a body provided with a recess having tapered guiding surfaces and a bottom wall with an axial opening therethrough for the reception of a pin stem, axially movable gripping means having a portion located in said recess and comprising a pair of gripping elements engaging said tapered surfaces to be moved toward each other by the surfaces as they move toward said bottom wall, a controlling member formed of resilient sheet material and folded into substantially inverted U-shape to have its leg portions confined and tending to spread apart and disposed between said gripping elements on opposite sides of said axial opening with the end portion of each leg extending outwardly to engage and support one of said elements to diametrically locate said elements on opposite sides of the axis of said opening and for movement of said elements axially away from said bottom wall whereby said elements are moved away from each other.

4. A pin stem clutch comprising a body provided with a recess having tapered guiding surfaces and a bottom wall with an axial opening therethrough for the reception of a pin stem, axially movable gripping means having a portion located in said recess and comprising a pair of gripping elements engaging said tapered surfaces to be moved toward each other by the surfaces as they move toward said bottom wall, a controlling member formed of resilient sheet material folded into substantially inverted U-shape to have its leg portions confined and tending to spread apart and disposed between said gripping elements on opposite sides of said axial opening with the end portion of each leg extending outwardly to engage and support one of said elements to diametrically locate said elements on opposite sides of the axis of said opening and tending to spread the elements apart for movement of said elements axially away from said end wall whereby said elements are moved away from each other, and a spring engaging said member to move it toward said wall.

5. A finding for pin stem clutch comprising an inverted U-shape sheet metal member having legs and means on the end portion of each leg for supporting gripping elements.

6. A finding for pin stem clutch comprising an inverted U-shape sheet metal member having legs, means on the end portion of each leg for supporting gripping elements and a tubular part axially extending therefrom into which the pin stem may extend.

7. A finding for pin stem clutch comprising an inverted U-shape sheet metal member having legs arched outwardly to provide bearings for roller gripping elements.

8. A finding for pin stem clutch comprising an inverted U-shape sheet metal member having legs arched outwardly to provide bearings for roller gripping elements and centrally recessed to receive a pin stem axially therethrough.

9. A finding for pin stem clutch comprising an inverted U-shape sheet metal member having legs arched outwardly to provide bearings for roller gripping elements and centrally recessed to receive a pin stem axially therethrough and a tubular part axially extending therefrom into which the pin stem may extend.
